UNITED STATES PATENT OFFICE.

JOHN A. L. GIST, OF CURIA, ARKANSAS, ASSIGNOR OF ONE-HALF TO ROBERT T. KERR, OF RANDOLPH, TEXAS.

DESIGN FOR A FIRE-SCREEN.

SPECIFICATION forming part of Design No. 23,337, dated June 5, 1894.

Application filed April 30, 1894. Serial No. 509,589. Term of patent 7 years.

To all whom it may concern:

Be it known that I, JOHN A. L. GIST, a citizen of the United States, residing at Curia, in the county of Independence and State of Arkansas, have invented a certain new and useful Design for Fire-Screens; and I do declare the following to be a full, clear, and exact description of the invention, such as will enable others skilled in the art to which it appertains to make and use the same, reference being had to the accompanying drawing, and to the letters of reference marked thereon, which form a part of this specification.

This invention relates to designs for fire-place screens and it has for its object the provision of a neat and ornamental design of the character mentioned.

The essential features of my design, which is clearly illustrated in the accompanying drawing, which, with the letters of reference marked thereon form a part of this specification, and in which drawing I have shown a front view of a fire-place screen embodying my design, are as follows, viz:

Two uprights A and B connected by transverse horizontal portions C and D, the vertical rods *a, a* passed through the horizontal rods C and D at regular intervals, the said vertical rods varying in length and at their upper ends being provided with balls or spherical ornaments and the rods of different lengths being relatively so arranged that a line passed through the upper ends of the series will be upon the arc of a circle. Ar-

ranged alternately between the rods *a, a* with 35 their longitudinal centers in the same horizontal plane with the upper bar C, are shorter rods *b, b*. These shorter rods *b* are also of varying lengths and are so placed as to cause the formation of an ellipse by drawing a line 40 through the upper and lower ends of the rods. The ends of the last mentioned rods are provided with spherical ornaments similar to those described as attached to the upper ends of the rods *a, a*, excepting that they are of 45 greater diameter. A series of rods *c, c* are likewise arranged alternately between the rods *a, a* at their lower ends; these rods *c* being of different lengths and so arranged that a line drawn through the upper ends of the series will be upon an arc of a circle, the said 50 upper ends of the rods being also provided with spherical ornaments. Directly in front of the transverse bars C and D appear ornamental strips E and F, to the center of the 55 upper strip E being attached a handle G.

Having thus described my design, what I claim to be new, and desire to secure by Letters Patent, is—

The design for a fire-place screen substantially as shown and described.

In testimony whereof I affix my signature in presence of two witnesses.

JOHN A. L. GIST.
